DESIGN FOR A FONT OF ARABIC TYPE

Seid J. Bustany, Detroit, Mich.

Application November 29, 1947, Serial No. 142,888

Term of patent 14 years

(Cl. D64—12)

To all whom it may concern:

Be it known that I, Seid J. Bustany, a citizen of the United States, residing in Detroit, county of Wayne, in the State of Michigan, have invented a new, original, and ornamental Design for a Font of Arabic Type, of which the following is a specification, reference being made to the accompanying drawing, forming part thereof:

Fig. 1 is a face view of the lower case of the font of Arabic type, showing my new design.

Fig. 2 is a face view of the capital letters of the same font of type.

Fig. 3 is a face view of the numerals of the same font of type.

I claim:

The ornamental design for a font of Arabic type, as shown.

SEID J. BUSTANY.
